UNITED STATES PATENT OFFICE.

SIXTE ARMAND COUPAL, OF GRANTS PASS, OREGON.

TENT.

Application filed August 13, 1926. Serial No. 129,007.

This invention relates to tents of the pyramidal type disclosed in my prior application, Serial No. 39,574, filed June 25, 1925, of which this application is a division in 5 part.

In the construction and use of tents of comparatively small size embodying my invention I have found it desirable and advantageous to arrange the main bracing connections between the frame staffs at the base of 10 the tent structure, whereby the desired bracing effect may be obtained without the necessity of employing sets of braces at different elevations between the upper and lower ends 15 of the staffs. One object of my present invention, therefore, is to provide a frame structure having bracing means of this character.

In this application I have also set forth 20 and claimed a type of coupler head for uniting the upper ends of the frame staffs, which coupler head was shown and described, but not claimed, in my aforesaid prior application.

25 The invention consists of the features of construction, combination and arrangement of parts, hereinafter fully described and claimed, reference being had to the accompanying drawings, in which:

30 Figure 1 is a perspective view of a set up tent constructed in accordance with my invention.

Figure 2 is a fragmentary perspective view 35 of the tetrapod truss frame, showing the bracing and coupling connections between the upper ends of the staffs.

Figure 3 is a sectional elevation, on an enlarged scale, showing the upper ends of two 40 of the staffs and the connection of the coupler ring and coupler head therewith.

Figure 4 is a section through the bottom of the tent, showing the horizontal brace connection between two of the staffs.

Figure 5 is a longitudinal section through 45 one of the staffs.

Figure 6 is a horizontal section through the upper ends of the staffs and the arms of the coupler head and showing the coupler ring in engagement therewith.

50 Figure 7 is a view in elevation looking toward the outer side of one of the staffs and the other parts shown in Figure 6.

Figure 8 is a section taken substantially on line 8—8 of Figure 7.

Figure 9 is a horizontal section through 55 one of the staffs and the end of the horizontal brace hinged thereto.

Figure 10 is a sectional plan view of a portion of the tetrapod frame showing two 60 of the staffs and the associated horizontal braces.

In carrying my invention into practice I provide a tent 1, made of canvas, ducking or other suitable material and having four sides or walls 2, each of triangular shape and 65 producing a tent body of pyramidal form. This tent body is provided with a floor or bottom wall 3, which may be of heavy canvas, ducking, or other heavy tent material, and which is joined to the lower edges of the 70 walls 2. This flexible tent bottom closes the base of the tent body against the entrance of dirt, dust, snow, rain, etc., and also against 75 the entrance of any disturbing gusts of air liable in stormy weather to disturb the equilibrium or stability of the tent structure. One of the walls 2 of the tent structure may be provided with any suitable type of door 4 to afford ingress and egress to the occupants thereof.

The tent body is held supported and its pyramidal conformation maintained by an internal framing having supporting and bracing characteristics. This framing is of tetrapod type and embodies four corner staffs 85 or legs 5, each preferably of extension type, said staffs being arranged at the corner angles of the walls along the fold lines thereof and extending from the bottom to the top or apex of the tent body. A form of extension staff which may be advantageously employed is shown in Figure 5, said staff comprising two telescopic sections 6 and 7, the top section 7 being adapted to telescope within and to be extended from the base section 6.

As shown, the section 6 is provided at its upper end with an inturned flange 8 and below the same with an inturned flange or stop 9, while the lower or inner end of the section 7 is formed to provide an outturned flange 10. The flange 10 of the section 7 is adapted to abut against the stop flange 9 of the section 5 when said section 7 is fully extended, and whereby its outward movement is limited. A spring-pressed latch pin 11 is provided at the lower end of section 7 for engagement with the flange 8 of the section 6 to hold the section 7 extended and

from collapsing. This latch member preferably is V-shaped and formed of spring wire and having its limbs provided with outturned locking arms or projections 12 movable in guide openings 13 in the section 7, the construction being such that the arms 12 will be normally pressed outward by the spring action of the limbs, so that said arms will move to projected position to overlie the flange 8 when the section 7 is drawn out to its fullest extent and will lock said section 7 from inward movement. When it is desired to collapse the section 7, this may be accomplished by pressing inwardly upon the arms 12 to cause them to recede and pass the flange 8 to permit the section 7 to be telescoped within the section 6.

The four extension props or legs 5, constructed as above-described, are adapted to be coupled at their upper ends and properly braced at their upper and lower ends to hold them in stack formation. For this purpose the sections 7 of the arms 5 are provided at their upper ends and in their outer sides with slots or notches 14 to receive a coupler band or ring 15, which holds them assembled and in properly spaced relationship. A coupler head 16 is provided for further uniting the upper ends of the staffs 5 and holding them in assembled relationship and locking the ring 15 against any possibility of casual displacement. This head comprises a pair of inverted U-shaped members 17, preferably made of spring strap metal and arranged at right angles to each other. The bights or return bend portions of these members are arranged in crossed relation and connected by a fastening means such as a bolt 18. The arms 19 of these members bear and are arranged so as to extend into the upper ends of the tubular leg sections 7 so as to lie between the slot engaging portions of the ring 15 and the wall portions of the members 7 above and below said slots so as to lock the ring against displacement from the slots and the legs from relative inward movement. Each arm 19 is provided with a locking pin or detent 20 to engage a keeper opening 21 in the section 7 to hold it in operative position. The locking pins are held in engagement with the keeper openings by the bowing or spring action of the arms 19, which have sufficient resiliency to permit them to be pressed back for a releasing action so that the parts can be readily disconnected when desired. This construction provides a type of bracing connection, in the form of the ring 15, and coupler connection in the form of the head 16, whereby the upper ends of the staffs will be held securely connected and braced, and which admits of their ready and easy assemblage and disassemblage. The bolt 18 may form a pivotal connection between the coupler members 17, whereby, when the coupler is disconnect-

ed, the parts thereof may be folded upon one another to lie nested, for greater convenience in storage and packing.

The staffs 5, when set up, are connected and braced at their upper ends by horizontal bracing members 22. Each of these bracing members 22 is preferably of folding and extension type and comprises a pair of sections 23 and 24, of the same general construction as the sections 6 and 7 of each staff, the section 24 being telescopic within and extensible from the section 23. The outer end of section 23 is provided with flanges 25 and 26 similar to flanges 8 and 9 of staff section 6, while section 24 is provided with a stop flange 27 similar to flange 10 of staff section 7, and the section 24 is further provided with a V-shaped latch member 28 having latch arms 29 extending outwardly through openings in the section 24 and adapted for locking engagement with the flange 27 to hold the section 24 against recession when in extended position. Each staff 5 carries one of the braces 22 which is detachably hinged thereto, the outer end of section 23 being provided with a flattened knuckle 30 fitting between the arms of a forked bracket 31 secured to the section 6 of the staff 5 and pivotally and detachably connected therewith by a cotter pin or other similar fastening member 32, the knuckle and arms of the bracket being perforated for the passage of said pin. The bracing member secured to each staff 5 is adapted to be disposed in a horizontal position between said staff and an opposite staff 5 of the frame and the outer end of its section 24 engaged in a receiving opening 33 in the latter-named staff, the section 6 of each staff being provided with an opening 33 for reception of the free end of a bracing member extending from another staff. When the bracing members are swung outward from the staffs to which they are hinged and engaged at their free ends with the opposed staffs, a rectangular bottom bracing frame will be formed extending along the walls of the tent adjacent to the bottom 3 and connecting the staffs at their lower ends in a firm and durable manner, as will be readily understood. By employing this bracing construction at the bottom of the tetrapod frame, a bracing connection of adequate strength for the frame below its top is provided for tents of comparatively small size, whereby the use of intermediate braces may be obviated and the tent structure simplified to that extent. When the staffs 5 are disconnected and collapsed in taking down the tent, the bracing members may also be collapsed and folded through their hinge pin connections 32 up against the collapsed staffs 5 and parallel therewith, so that the parts of the frame structure may be conveniently fastened together for package in close compass for stor-

age or transportation. The construction described also adapts the brace members to be disconnected from the staffs for separate packing when desired or for convenience in repairing the parts of the frame or substituting new parts for damaged ones.

The tent may be set up for use by placing the tetrapod frame elements on the inside of the tent body and erecting the frame structure in an obvious manner, which operation may be performed within a very short space of time. By reversing this operation, the frame structure may be disassembled and the parts thereof collapsed and packed with the collapsed tent in very close compass for storage or transportation. It will thus be seen that the tent structure affords great convenience in setting up and taking down operations, as well as in transporting the same on marches or from place to place for use, and in storing the same away when its use is not required.

The present invention provides a tent structure which is of a geometric formation like that disclosed in my aforesaid prior application, No. 39,574, with the same advantage of great strength and maximum resistance against weight collapse or wind pressures, and in which the frame structure is such as to reduce the number of frame parts to a minimum, without sacrifice of strength, so that small tent structures of great strength and convenient character may be produced at a comparatively low cost. Other advantages of the invention will be apparent from the foregoing description.

Having thus fully described my invention, I claim:—

1. A tent structure comprising a pyramidal tent body, and an internal bracing frame for the tent body consisting of staffs at the corners of the tent body, a coupling ring uniting said staffs at their upper ends, a coupler head joining said staffs at their upper ends and holding said ring from displacement, and coupling means uniting said staffs at their lower ends.

2. A tent structure comprising a pyramidal tent body, and an internal bracing frame for the body consisting of telescopic staffs at

the corners of the body, a coupling ring uniting said staffs at their upper ends, a coupler head joining said staffs at their upper ends and holding said ring from displacement, and coupling and bracing means uniting said staffs at their lower ends.

3. A tent structure comprising a pyramidal tent body, telescopic sustaining staffs at the corners of the tent body, a coupling ring uniting said staffs at their upper ends, a coupler head joining said staffs at their upper ends and holding said ring from displacement, and telescopic connecting and bracing means between the lower ends of the staffs.

4. A tent structure comprising a pyramidal tent body, staffs having slots at their upper ends, a coupler ring engageable with said slots, and a coupler head having arms adapted for interlocking engagement with the staffs and forming latches to hold the coupler ring from displacement.

5. A tent structure comprising a pyramidal tent body, tubular staffs having slots at their upper ends, a coupler ring engageable with said slots, and a coupler head having arms adapted to fit within the upper ends of the staffs and to be engaged with the ring to hold the ring from displacement, said arms having latches to engage the staffs.

6. A tent structure comprising a pyramidal tent body, staffs at the corners of the tent body comprising telescopic sections, means for detachably coupling and bracing the staffs at their upper ends, and telescopic braces for uniting the staffs at their lower ends, each staff comprising telescopic sections, one of said sections being hinged to a staff and the other section detachably engageable with another staff.

7. A sustaining frame for tents comprising staffs, braces for connecting the staffs at their lower ends, a coupler ring detachably engaging the upper ends of the staffs, and a coupler head having arms detachably engaging the upper ends of the staffs and forming latches holding the ring from displacement.

In testimony whereof I affix my signature.

SIXTE ARMAND COUPAL.
